UNITED STATES PATENT OFFICE.

ALEXANDER McLEAN NICOLSON, OF TARRYTOWN, NEW YORK, ASSIGNOR, BY MESNE ASSIGNMENTS, TO WESTERN ELECTRIC COMPANY, INCORPORATED, A CORPORATION OF NEW YORK.

VACUUM-TUBE DEVICE.

1,196,474.

Specification of Letters Patent. Patented Aug. 29, 1916.

Application filed October 27, 1914. Serial No. 868,840.

To all whom it may concern:

Be it known that I, ALEXANDER McLEAN NICOLSON, a subject of the King of Great Britain, residing at Tarrytown, in the county 5 of Westchester and State of New York, have invented certain new and useful Improvements in Vacuum-Tube Devices, of which the following is a full, clear, concise, and exact description.

10 This invention relates to vacuum tubes or vessels and more particularly to thermionic devices of the audion type.

The object of this invention is to provide a new and improved form of thermionic device of compact structure and one which may be operated efficiently on high power 15 circuits.

In accordance with the general features 20 of this invention there is provided a vessel for the audion in which the electrodes may be located closely adjacent the walls; the vessel is also constructed in such a manner that the electrodes may be located adjacent opposing walls, either or both of which may 25 have extraneous cooling means applied thereto.

In the drawings Figure 1 is a view in side 30 elevation with parts in section of a device illustrating one form of the invention. Fig. 2 is sectional view of the device taken upon line 2—2 of Fig. 1. Fig. 3 is a view illustrating one method of applying the cooling means and Fig. 4 illustrates another method by means of which the apparatus may be 35 cooled.

In the form of the device illustrated, the vessel for the audion comprises two concentric cylindrical walls 5 and 6 closed at 40 their ends to form an enclosure for the anode or output electrode 7, the filament 8 and the input element or electrode 9. The outside of the cylindrical wall 5 and the inside of the cylindrical wall 6 are both exposed so that cooling means may be readily applied 45 thereto.

The anode or output electrode 7 is cylindrical in shape and of substantially the same diameter as the inner surface of the outer cylindrical wall 5 so that when in position 50 for operation this electrode 7 will be held in place by frictional engagement with the adjacent surface of the wall 5. The input

element or inner electrode 9 is also cylindrical in form and is adapted to embrace the inner cylindrical wall 6 of the vessel and be 55 supported thereby. The filament 8 may take the form of a coil spiraled around the inner electrode 9 as shown in the drawings. Conductors 10, 11, 12 and 13 may be led into the elements in the usual manner for vacuum 60 tubes, the conductor 10 being connected with the electrode 7, the conductor 11 with the electrode 9 and the conductors 12 and 13 with the opposite ends of the filament 8. The conductor 13 which is attached to one 65 end of the filament 8 is led through a glass tube or insulating bushing 15 located between the inner surface of the wall 5 and the electrode 7 in a depression 16 formed in said electrode 7.

In Fig. 3 the device previously described is shown as immersed in a cooling fluid 20 contained within a vessel 21.

In Fig. 4 the cooling means is applied only to the inner wall by circulation. In this 75 scheme a cooling tank 25, is placed above the device and tubes 26 and 27 opening into said tank are led into the opposite ends of the inner cylinder 6 through suitable stoppers 28 and 29. In this arrangement only the inner 80 wall 6 is cooled by the fluid, the outer wall 5 being cooled sufficiently by radiation.

By reason of the location of the electrodes adjacent opposing walls which are accessible for the application of cooling means 85 there is provided an efficient and compact structure capable of being worked on high power circuits without danger of the detrimental phenomenon heretofore experienced.

The invention claimed is:

1. In a thermionic device of the audion type, a containing vessel having opposing walls, a pair of separated electrodes comprising conducting coatings on the inner surfaces of said walls and conforming thereto, and means for cooling the outer surfaces of said walls.

2. In a thermionic device of the audion type, an evacuated vessel having opposing walls, a pair of separated electrodes comprising conducting coatings of uniform thickness on the inner surfaces of said walls, and means for cooling said walls.

3. In a thermionic device of the audion

type, a pair of concentrically arranged electrodes, a containing vessel having inner and outer concentrically arranged walls closely adjacent said electrodes, and cooling means 5 for the walls of said vessel.

4. In a thermionic device of the audion type, a vessel comprising concentrically arranged walls connected together at both ends, output and input electrodes located 10 closely adjacent the inner faces of said walls, and a cathode located between said electrodes.

5. In a thermionic device of the audion type the combination of a vessel comprising 15 concentric cylindrical walls closed at each end between said walls and open within the inner tube, a cylindrical input electrode surrounding and closely adjacent the inner cylindrical wall of said vessel, a cylindrical 20 output electrode within and closely adjacent

the outer cylindrical wall thereof, and a cathode between said electrodes.

6. In a thermionic device of the audion type the combination of a vessel comprising concentric tubular walls closed at each end 25 between said walls and open within the inner tube, a cylindrical input electrode surrounding and closely adjacent the inner tubular wall of said vessel, a cylindrical output electrode within and closely adjacent the 30 outer tubular wall thereof, and a cathode in the form of a spiral filament surrounding said input electrode.

In witness whereof, I hereunto subscribe my name this 26 day of October A. D., 1914. 35

ALEXANDER MCLEAN NICOLSON.
